CLAIM

The ornamental design for a flume channel, as shown and described.

DESCRIPTION

This application is being filed contemporaneously with U.S. Nonprovisional application Ser. No. 16/582,612, entitled Basement Drainage System with Flume Channel, which is hereby incorporated in its entirety by reference herein.

FIG. 1 is a front perspective view of a flume channel showing my design;

FIG. 2 is a rear perspective view of the flume channel shown in FIG. 1;

FIG. 3 is a front elevation view of the flume channel shown in FIGS. 1 and 2;

FIG. 4 is a side elevation view of the flume channel shown in FIGS. 1-3, with the opposite side elevation being a mirror image thereof;

FIG. 5 is a rear elevation view of the flume channel shown in FIGS. 1-4;

FIG. 6 is a a to view of the flume channel shown in FIGS. 1-5; and,

FIG. 7 is a bottom view of the flume channel shown in FIGS. 1-6.

The broken lines shown in the drawings show portions of the flume channel that form no part of the claimed design. The flume channel is shown with a symbolic break in its length. The appearance of any portion of the flume channel between the break lines form no part of the claim.
